UNITED STATES PATENT OFFICE

ALEXANDER W. SANSBURN, OF PILARES DE NACOZARI, MEXICO

LAMP BRACKET

Application filed October 8, 1928. Serial No. 311,193.

The present invention is directed to improvements in lamp brackets.

The primary object of the invention is to provide a device of this character so constructed that the lamp can be conveniently adjusted vertically when desired and can also swing in a horizontal plane.

Another object of the invention is to provide a device of this character so constructed that it can be easily and quickly applied and is so arranged that the current conducting wire can be easily applied thereto.

Another object of the invention is to provide a device of this character so constructed that the lamp will be supported upon its current conducting wire, said wire serving also for supporting a counterbalance.

With these and other objects in view, this invention resides in the novel features of construction, formation, combination and arrangement of parts to be hereinafter more fully described, claimed and illustrated in the accompanying drawings, in which:—

Figure 1 is a side elevation of the device, partly in section.

Figure 2 is a similar view of a modified form of the invention.

Figure 3 is a modified form of the invention showing the same when in use in connection with a kerosene or other fluid burning lamp.

Figure 4 is a side view partly in section, of another modified form of the invention.

Referring to the drawings 1 designates a portion of a ceiling and to which is secured a block 2, said block having threaded therein the upper end of a tube 3, said tube having rotatably engaged thereon a union 4. In order to maintain the union in place the lower end of the tube 3 has connected thereto a cap 5 which will obviously maintain the union in place but at the same time permit the same to rotate freely upon the tube.

In this form of the invention a pair of diametrically opposed tubular arms 6 are provided, said arms having their inner ends threaded in the sockets 7 of the union 4. To the upper ends of these arms are threaded T's 8 in which are rotatably engaged tubes 8' to the lower ends of which are connected T's

9, the latter T's having engaged therewith tubular arms 10 and 11, each of which having secured thereto a clip 12 and 13, which rotatably support pulleys 14 and 15, respectively. It will be observed that the pulleys 14 will be located adjacent the outer ends of the arms 10, whereas the pulley 15 will be supported intermediate the ends of the arms 11. The tube 8' is retained in the T 8 by a cup 15'.

The electrical conducting wires 16 are passed through the tube 3 and thence through perforations 17 formed in the arms fixed adjacent the inner ends thereof, said wires being extended longitudinally along the arms 6 and are then passed through grouped perforations 18 and thence through the T's 8 and 9 and through the perforations 19 of the arms 11. The wires are then passed through perforations 20 formed in the inner ends of arm 11 where a loop 21 is formed, said loop having engaged therewith a pulley 22 which supports the counterweight 23.

The wires are trained over the pulleys 15 and 14 and have their terminals connected to a lamp socket 24 in which is engaged an incandescent bulb 25, there being a shade 26 for the bulb.

The weight of the lamp and its shade are such that the weight 23 will counterbalance the same in order that the lamp can be raised or lowered and maintained in any selected position. Since the arms 6 are rotatably engaged on the tube 3 it is apparent that the lamp can be swung in a horizontal plane to position the same where needed.

In Figure 2 there is illustrated a single unit which is supported by a wall 27 and to which is secured vertically spaced brackets 28 for rotatably supporting the vertical rod 29, the upper end of which has secured thereto a union 30. The union supports the horizontally disposed tubular arms 31 and to which is connected the arms 32 and 33, and since these arms support the lamp 34 and weights 35 in the same manner as that disclosed in the preferred form of the invention a detail description thereof is not thought necessary.

The lower end of the rod 29 is rotatably supported upon the bracket 36 which will ob-

viously prevent downward movement of the rod, but will permit the same to rotate freely when it is desired to swing the lamp 34. In this instance the current conducting wire 37 leads from a switch 38 carried by the wall.

5 In Figure 3 there is illustrated a rod 38 which is rotatably supported by brackets 39, said rod having an arm 40 fixed to its upper end and to which is carried the arms 41 and 42, said arms supporting the pulleys 43 and 44 and around which are trained a chain 45, one end of the chain being fixed to the inner ends of the arm 42 while the other end of said chain has carried thereby rods 46 which support a holder 47 for receiving a fluid burning lamp 48. A counterweight 49 is employed and has carried thereby a pulley 50 which engages the chain and operates in the same manner as the weight illustrated in the other forms of the invention.

20 In the modified form as shown in Figure 4, the tubular arm 51 is connected to the ceiling in the same manner as the arms of the preferred form. The arm 51 has carried upon its outer end a T 52 in which is rotatably mounted a tube 53 and rotatably engaged upon the lower end of the tube is a T 54, said tube having caps 55 and 56 threaded upon its upper and lower ends to maintain the parts 25 in assembled relationship. Threaded in the T 54 is a tubular arm 57 having rotatably mounted thereon pulleys 58 and 59 and over which the conductor 60 is trained, said conductor being also passed through the tube 53 and looped as at 61 for engagement with the pulley 52 carried by the counterweight 63. The outer end of the conductor has fixed thereto a socket 64 for supporting the incandescent bulb 65.

40 The counterweights are preferably of bowl like formation in order that weights may be placed therein to accurately counterbalance the lamp.

45 It will thus be seen that a bracket has been provided so constructed that the lamp can be conveniently swung in a horizontal plane to various points, and adjusted vertically in a simple and practical manner.

50 From the foregoing, it is thought that the construction, operation and many advantages of the herein described invention will be apparent to those skilled in the art, without further description, and it will be understood that various changes in the size, shape and 55 proportion and minor details of construction, may be resorted to without departing from the spirit or sacrificing any of the advantages of the invention.

55 What is claimed is:—

60 1. A lamp bracket comprising a supporting tube, a horizontal arm rotatably engaged with said tube, arms rotatably connected to the first named arm, a current conducting wire leading from the tube and engaged with 65 said arms and disposed upon opposite sides

of its pivotal connection, pulleys carried by the fixed arms, said wire being trained over the pulleys, a lamp carried by one of the terminals of the wire, and a counterweight having a pulley carried thereby and engaged with the wire intermediate its ends for counterbalancing the lamp.

70 2. A lamp bracket comprising a rotatably supported arm, arms having their opposed ends rotatably connected therewith, and having clips carried thereby, pulleys carried by the clips, a current conducting wire extending longitudinally of all of said arms and trained round said pulleys, said wire being looped intermediate its ends, a counterweight having a pulley carried thereby and engaging the looped portion of the wire, and a lamp secured to the outer terminal of the wire.

75 3. A lamp bracket comprising a vertical rod, means for pivotally connecting the rod to a support, a horizontal arm fixed to and rotatable with the rod, a pair of arms having their opposed ends rotatably connected with the fixed arm, a pulley fixed to each arm of the pair of arms, a chain having one of its terminals fixed to one of the paired arms and trained over both pulleys, the other terminal having a holder connected therewith, a lamp in the holder, said chain being looped intermediate its terminals, and a counterweight having a pulley carried thereby and engaging the looped portion of the chain for counterbalancing the lamp.

80 4. A lamp bracket comprising a rotatably supported horizontal arm, a T carried by the outer end thereof, a tube engaged in the T, a second T engaged on the tube, said tube being rotatable in the T's, a pair of horizontal arms having their opposed ends engaged in the second T, a current conducting wire passing through the tube and movably supported upon the last named arm, a lamp supported upon one end of the wire, and a counterweight engaged with the intermediate portion of the wire for counterbalancing the lamp.

85 In testimony whereof I affix my signature.

ALEXANDER W. SANSBURN. [L.S.]
